(57) **CLAIM**

The ornamental design for a hood for construction machinery, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a hood for construction machinery according to the present invention.

FIG. 2 is a front view of the hood for construction machinery of FIG. 1.

FIG. 3 is a rear view of the hood for construction machinery of FIG. 1.

FIG. 4 is a left side view of the hood for construction machinery of FIG. 1.

FIG. 5 is a right side view of the hood for construction machinery of FIG. 1.

FIG. 6 is a top view of the hood for construction machinery of FIG. 1; and,

FIG. 7 is a bottom view of the hood for construction machinery of FIG. 1.

The broken lines and the dot-dash broken lines form no part of the claimed design.
